UNITED STATES PATENT OFFICE.

MILLARD FILLMORE ANDERSON, OF NEW YORK, N. Y.

TRIMMING-MACHINE FOR ROLLS.

1,139,322.

Specification of Letters Patent. Patented May 11, 1915.

Application filed May 8, 1914. Serial No. 837,296.

To all whom it may concern:

Be it known that I, MILLARD F. ANDERSON, a citizen of the United States, and a resident of the city of New York, Belle Harbor, borough of Queens, in the county of Queens and State of New York, have invented a new and Improved Trimming-Machine for Rolls, of which the following is a full, clear, and exact description.

10 The object of the invention is to provide a new and improved machine for simultaneously trimming both ends of a roll of oil-cloth or other material, and arranged to permit convenient adjustment of the knives or cutters for trimming rolls of different length.

In order to accomplish the desired result use is made of a driven supporting roller for supporting a roll and rotating the same, 20 a driven abutment roller for one side of the roll to abut against, spaced rotary knives or circular cutters for cutting the ends of the roll, and means for moving the said rollers and the said knives bodily one relatively to the other.

A practical embodiment of the invention is represented in the accompanying drawings forming a part of this specification, in which similar characters of reference indicate corresponding parts in all the views.

Figure 1 is a sectional side elevation of the trimming machine; Fig. 2 is a plan view of the same; Fig. 3 is a front elevation of the same; Fig. 4 is an enlarged cross section of 35 the carriage and its bearing on the main frame; Fig. 5 is an enlarged plan view of the adjustable roller on the carriage; Fig. 6 is a cross section of the same on the line 6—6 of Fig. 5; and Fig. 7 is an enlarged 40 cross section of one of the revolute knives or cutters and its mounting.

The improved trimming machine is mounted on a suitably constructed frame A provided with fixed bearings A' in which 45 is journaled a shaft B provided at its ends with adjustable and revolute circular cutters or knives C for trimming the ends of a roll D of oilcloth or other material, as hereinafter more fully described.

50 The roll D is supported on one or a series of rollers E, and one side of the roll D rests on or abuts against one of the series of abutment rollers F, the said rollers E and F

being secured on shafts E' and F' journaled in suitable bearings arranged on the carriage G mounted to reciprocate on suitable guideways A² arranged transversely on the main frame A. Both rollers E and F are driven in the direction of the arrows in Fig. 1 to rotate the roll D, and on moving the carriage G rearwardly the roll D is carried along with the rollers E and F and is hence fed to the rotary knives or cutters C to trim the ends of the roll D.

In order to hold the roll D in place on the supporting rollers E and the abutment rollers F use is made of one or a series of bearing rollers H attached to a shaft H' journaled in suitable bearings arranged on a swing frame I fulcrumed on a shaft J journaled in suitable bearings arranged on the rear end of the carriage G. The forward end of the swing frame I is provided with a handle I' adapted to be taken hold of by the operator to swing the forward end of the frame I 70 downward with a view to move the bearing rollers H in engagement with the top of the roll D to hold the latter in position during the trimming operation by the knives or cutters C. The rear end of the swing frame I 75 is provided with a counterweight I² to hold the swing frame I with its forward end normally in a raised position, as indicated in full lines in Fig. 1, to permit of conveniently placing the roll D in position on the supporting rollers E and the abutment roller F, or for removing the trimmed roll D from the said rollers E and F.

In order to rotate the rollers E and F and the knives or cutters C prior to moving the carriage G rearwardly with a view to feed the roll D to the said knives or cutters the following arrangement is made: On the main frame A is mounted a motor K of any approved construction and provided on its shaft with a pinion K' in mesh with an intermediate gear wheel K² secured on a shaft K³ provided with a pinion K⁴ in mesh with a gear wheel K⁵ mounted to rotate loosely on a shaft L journaled in suitable bearings 100 arranged on the main frame A the same as the shaft K³. The gear wheel K⁵ is provided with a clutch member K⁶ adapted to be engaged by a clutch member L' mounted to slide on and to rotate with the shaft L. 105 A spring L² is interposed between the clutch

- members K^6 and L' to normally hold the clutch member L' out of engagement with the clutch member K^6 to allow the gear wheel K^5 to rotate loosely on the shaft L .
- 5 The clutch member L' is engaged by a shifting lever L^3 fulcrumed at its lower end and at L^4 on a suitable bracket attached to the floor and the upper end of the said shifting lever L^3 is connected by a link L^5 with one end of 10 a coil spring L^6 connected at its other end with an arm L^7 projecting upwardly from a pedal shaft N journaled in suitable bearings arranged on the main frame A . On the pedal shaft N is secured a pedal N' under the control of the foot of the operator standing in front of the machine so that when the pedal N' is pressed downward a short distance then a rocking motion is given to the shaft N to cause the arm L^7 to 15 exert a pull on the spring L^6 which by the link L^5 imparts a swinging motion to the shifting lever L^3 to move the clutch member L' into engagement with the clutch member K^6 to cause the gear wheel K^5 to rotate the 20 shaft L by the engaged clutch members K^6 and L' . When the operator releases the pressure on the pedal N' , the spring L^6 forces the clutch member L' out of engagement with the clutch member K^6 to stop the 25 further rotation of the shaft L . On the shaft L is secured a sprocket wheel O connected by a sprocket chain O' with a sprocket wheel O^2 secured on the shaft J previously mentioned, and on the said shaft 30 35 J is secured a sprocket wheel J' connected by a sprocket wheel J^2 with sprocket wheels J^3, J^4 secured on the shafts E' and F' respectively, so that when the shaft L is rotated a rotary motion is given to the rollers 40 E and F to rotate the same in the direction indicated by the arrows shown in Fig. 1. As the shaft J above mentioned is journaled on the carriage G the sprocket chain O' has to be kept taut by the use of a tight- 45 50 ening sprocket wheel O^3 in mesh with one of the runs of the sprocket chain O' , the said sprocket wheel O^3 being journaled on an arm O^4 fulcrumed on the main frame and pressed on by a spring O^5 to cause the sprocket wheel O^3 to bear against the chain O' with a view to hold the same taut.

On the shaft L is secured a sprocket wheel P connected by a sprocket chain P' with a sprocket wheel P^2 secured on the shaft B 55 so that when the shaft L is rotated as previously explained then a rotary motion is transmitted by the sprocket wheels P and P^2 and the sprocket chain P' to the shaft B to rotate the knives or cutters C in the direction of the arrows indicated in Fig. 1.

In order to impart a reciprocating motion to the carriage G with a view to feed the roll D past the cutters or knives C , the following arrangement is made: On the

shaft L is secured a pinion Q in mesh with a gear wheel Q' mounted to rotate loosely on a cam shaft R journaled on the main frame A . On one face of the gear wheel Q' (see Fig. 3) is secured or formed a clutch member Q^2 adapted to be engaged by a clutch member Q^3 mounted to slide on and rotate with the shaft R . A spring Q^4 is interposed between the clutch members Q^2, Q^3 to normally hold the clutch member Q^3 out of engagement with the clutch member Q^2 . By reference to Fig. 3 it will be noticed that normally the clutch member Q^3 is held a greater distance apart from its clutch member Q^2 than the distance between the clutch members L' and K^6 . The clutch member Q^3 is controlled by a shifting lever Q^5 fulcrumed at Q^6 on the main frame A , and the said shifting lever Q^5 is pivotally connected by a link Q^7 with an arm Q^8 depending from the pedal shaft N . Now when the pedal N' is pressed a short distance downward then the clutch member L' is moved in engagement with the clutch member K^6 , but when this takes place the clutch member Q^3 is close to but is still out of engagement with the clutch member Q^2 , and on further downward pressing of the pedal N' the clutch member Q^3 is moved into engagement with the clutch member Q^2 so that the shaft R is driven from the gear wheel Q' now driven by the pinion Q from the now rotating shaft L .

It will be noticed that after the clutch members L' and K^6 are in engagement and the pedal N' is further pressed downward then the spring L^6 is expanded to allow a downward movement of the pedal lever N to move the clutch Q^3 into engagement with the clutch Q^2 .

On the cam shaft R is secured a cam R' engaging with its peripheral face a friction roller R^2 held on the lower end of a shifting lever R^3 fulcrumed at R^4 on the main frame A . The upper end R^5 of the shifting lever R^3 is in the form of a fork engaging a friction roller S adjustably mounted on a bracket S' attached to the carriage G so as to move with the same. The friction roller S has its stud S^2 (see Figs. 5 and 6) provided with a head S^3 and a square offset S^4 fitting into a slot S^5 formed in the bracket S' . In the head S^3 screws a screw rod S^6 journaled in bearings S^7 attached to or forming part of the bracket S' so that when the screw rod S^6 is turned by the operator then the head S^3 is moved longitudinally on the bracket S' to move the friction roller S into a desired position to hold the rollers E and F in proper position relatively to the knives or cutters C according to the diameter of the roll D to be trimmed at the time.

A nut and washer S^8 are held on the threaded extension S^9 of the square offset

5 S^4 to fasten the head S^3 in place on the shaft S' after the desired adjustment is made. The shifting lever R^3 is provided with an angular arm R^6 (see Fig. 1) connected at its free end with one end of a spring R^7 attached at its other end to the main frame A so as to impart a return swinging motion to the shifting lever R^3 at the time the friction roller R^2 drops off of 10 the end of the cam R' as will be readily understood by reference to Fig. 1.

The carriage G is provided at the under side of each of its side arms with an integral bar G' , provided at the under side with 15 bevels G^2 and G^3 extending in opposite directions and engaging conical rollers T and T' contained in the U-shaped guideway A^2 and having their shaft T^2 journaled in a bearing T^3 provided with a pin T^4 engaging 20 a socket A^3 formed in the bottom of the guideway A^2 . By this arrangement an easy forward and backward sliding movement of the carriage G is had, it being understood that the guideways A^2 are preferably filled 25 with oil to keep the carriage G properly lubricated.

30 By reference to Fig. 2, it will be noticed that the bearings A' for the shaft B are intermediate the two knives or cutters C to allow shifting of the knives or cutters C on the ends of the shaft B with a view to move the knives or cutters C the desired distance apart according to the length of the roll D to be trimmed at the time.

35 In order to allow convenient shifting of each cutter or knife C on the shaft B and to securely fasten the same in position on the shaft after the desired adjustment is made the following construction is provided, special reference being had to Fig. 7: Each 40 knife or cutter C is clamped between flanges C' , C^2 of which the flange C' is fixed on the hub C^3 while the flange C^2 screws on a threaded portion of the hub C^3 and is locked 45 in place by a jam nut C^4 screwing on the hub. The hub C^3 has a conical bore and fits onto a conical split sleeve C^5 fitting the shaft B , and the small end of the sleeve C^5 is threaded and on this threaded portion 50 screws a nut C^6 abutting against the small end of the hub C^3 . On screwing up the nut C^6 the hub C^3 is pushed up on the sleeve C^5 whereby the hub is tightened on the shaft B and is consequently clamped thereto, and 55 at the same time the hub C^3 is drawn tight on the conical sleeve C^5 . When it is desired to change the position of a knife or cutter C it is only necessary to partly unscrew the nut C^6 to release the hub C^3 which in turn 60 releases the sleeve C^5 to allow of shifting the latter on the shaft B until the knife or cutter C recedes to the desired position. When this position is reached the nut C^6 is again screwed up to fasten the hub C^3 in

place on the sleeve C^5 on the shaft B . When 65 it is desired to remove a knife or cutter C from its hub C^3 for grinding or other purposes then the nut C^4 and the flange C^2 are unscrewed from the hub C^3 to allow removal of the knife or cutter C .

70 The operation is as follows: When the carriage G is in forward position and the swinging frame I is in uppermost position then the operator can conveniently place a roll D to be trimmed in position on the rollers E and F so that the roll D is in front of the knives or cutters C . The operator now takes hold of the handle I' and swings the frame I downward so that the bearing rollers H engage the top of the roll D . The operator now presses the pedal lever N downward so that the shifting lever L^3 moves the clutch member L' in engagement with the clutch member K^6 to cause the continually rotating gear wheel K^5 to rotate the shaft 85 L . As soon as the shaft L is rotated a rotary motion is given to the rollers E and F and the knives or cutters C and then the operator presses the pedal lever N still farther downward to cause the clutch member 90 Q^3 to engage the clutch member Q^2 so that the cam shaft R is now rotated. The rotary motion of the shaft R causes its cam R' to impart a swinging motion to the shifting lever R^3 whereby the carriage 95 G is moved thereby carrying the rotating roll D along and thus feed the same to the knives or cutters C . The knives or cutters now trim the ends of the roll D , it being understood that the trimming operation is 100 completed when the friction roller R^2 drops off the end of the cam R' , and the carriage G is now returned by the action of the spring R^7 imparting a return swinging motion to the shifting lever R^3 . As soon as the 105 carriage G reaches its forward position the operator swings the swing frame I upward and then removes the trimmed roll D from the rollers E and F and places another 110 untrimmed roll in position thereon. The above described operation is then repeated.

115 It is understood that as the roll D is rotated by contact with the driven rollers E and F it is evident that the carriage G needs to be fed only a distance slightly in excess of half of the diameter of the roll D . By adjusting the friction roller S on the bracket S' , as previously explained, the carriage G may be moved farther outward or inward to suit the diameter of the roll D 120 to be trimmed at the time, and the knives or cutters C can be adjusted on the shaft B to suit the length of the roll D to be trimmed at the time.

Having thus described my invention, I 125 claim as new and desire to secure by Letters Patent:

1. A trimming machine for rolls, com-

prising a driven supporting roller for supporting a roll and rotating the same, a driven abutment roller for one side of the roll to abut against, a bearing roller located on one side of said supporting roller and higher up to form an abutment bearing on the top of the roll, spaced rotary knives located on the other side of the said supporting roller for cutting the ends of the roll, and means for moving the said rollers and the said knives bodily one relatively to the other.

2. A trimming machine for rolls, comprising a driven supporting roller for supporting a roll and rotating the same, a driven abutment roller located on one side of the said supporting roller and higher up to form an abutment for one side of the roll to abut against, a swing frame provided with a bearing roller adapted to engage the top of the roll, spaced rotary knives located on the other side of the said supporting roller and adapted to cut the ends of the roll, and means for bodily moving the said rollers and knives one relatively to the other.

3. A trimming machine for rolls, comprising a driven supporting roller for supporting a roll and rotating the same, a driven abutment roller for one side of the roll to abut against, a swing frame provided with a bearing roller adapted to engage the top of the roll, spaced rotary knives adapted to cut the ends of the roll, fixed bearings for the said knives, a carriage on which the said supporting roller and the said abutment roller are journaled and on which carriage the said swing frame is fulcrumed, and means for imparting a reciprocating movement to the said carriage.

4. A trimming machine for rolls, comprising spaced rotary knives, a reciprocating carriage, a driven supporting roller journaled on the said carriage and adapted to support and rotate a roll to be trimmed, a driven abutment roller journaled on the said carriage adjacent the said supporting roller and higher up to form an abutment for one side of the roll, and means for imparting a reciprocating motion to the said carriage.

5. A trimming machine for rolls, comprising spaced rotary knives, a reciprocating carriage, a driven supporting roller journaled on the said carriage and adapted to support and rotate a roll to be trimmed, a driven abutment roller journaled on the said carriage adjacent the said supporting roller and higher up to form an abutment for one side of the roll, a manually controlled swing frame fulcrumed on the said carriage, a bearing roller journaled on the said swing frame, and means for imparting a reciprocating movement to the said carriage.

6. A trimming machine for rolls, comprising spaced rotary knives journaled in sta-

tionary bearings, a reciprocating carriage, a supporting roller journaled on the said carriage and adapted to support and rotate a roll to be trimmed, an abutment roller journaled on the said carriage and positioned to form an abutment for one side of the said roll, driving means for simultaneously supporting the said knives and the said rollers, a shifting device for imparting a reciprocating motion to the said carriage, and manually controlled means for successively starting the said driving means and the said shifting device.

7. A trimming machine for rolls, comprising spaced rotary knives journaled in stationary bearings, a reciprocating carriage, a supporting roller journaled on the said carriage and adapted to support and rotate a roll to be trimmed, an abutment roller journaled on the said carriage, and positioned to form an abutment for one side of the said roll, a cam and lever mechanism connected with the said carriage for imparting a reciprocating motion to the carriage, a driving gear for rotating the said rollers and the said knives simultaneously, and manually controlled means for successively starting the said driving gear and the said cam and lever mechanism.

8. A trimming mechanism for rolls, comprising spaced rotary knives journaled in stationary bearings, a reciprocating carriage, a supporting roller journaled on the said carriage and adapted to support and rotate a roll to be trimmed, an abutment roller journaled on the said carriage and positioned to form an abutment for one side of the said roll, a manually controlled frame fulcrumed on the said carriage, a bearing roller journaled on the said swing frame and adapted to bear down on the top of the roll, driving means for simultaneously rotating the said knives and the said rollers, a shifting device for imparting a reciprocating motion to the said carriage, and manually controlled means for successively starting the said driving means and the said shifting device.

9. A trimming machine for rolls, comprising spaced rotary knives journaled in stationary bearings, a reciprocating carriage, a supporting roller journaled on the said carriage and adapted to support and rotate a roll to be trimmed, an abutment roller journaled on the said carriage and positioned to form an abutment for one side of the said roll, a shaft provided with a pinion, a driven gear wheel loose on the said shaft, a clutch for connecting the said gear wheel with the shaft to rotate the latter, a cam shaft, a gear wheel loose on the said cam shaft and in mesh with the said pinion, a clutch on the said cam shaft for connecting the gear wheel thereon with the cam shaft, a pedal mechanism connected with the said clutches to ac-

tuate the clutches successively, a cam and lever mechanism connecting the said cam shaft with the said carriage, and a driving gear connecting the said first-named shaft 5 with the said roller and knives to rotate the rollers and knives simultaneously prior to starting the carriage.

In testimony whereof I have signed my name to this specification in the presence of two subscribing witnesses.

MILLARD FILLMORE ANDERSON.
